United States Patent Office.

ISAAC P. RICHARDS, OF WHITINSVILLE, MASSACHUSETTS.

Letters Patent No. 92,647, dated July 13, 1869.

IMPROVEMENT IN SPINDLE-BOLSTERS.

The Schedule referred to in these Letters Patent and making part of the same

To all whom it may concern:

Be it known that I, ISAAC P. RICHARDS, of Whitinsville, in the county of Worcester, and State of Massachusetts, have invented a new and useful Improvement in Spindle-Bolsters; and I do hereby declare that the following specification, taken in connection with the drawings, making a part of the same, is a full, clear, and exact description thereof.

Figure 1 is a side elevation.

Figure 2 is a top view.

Figure 3 is a view in section.

Many devices have heretofore been contrived for supplying a bolstered spindle, or rapidly-revolving shaft, with a constant supply of oil, whose flow to the bearing shall be regulated by the necessities of the case. Many of these devices employ the principle of the capillary attraction existing in fibrous materials, as a means for conducting the lubricant to the bearing. My invention consists in a peculiar construction of the oil-reservoir, whereby the current created by a rapidly-revolving spindle or shaft, is made available in drawing the lubricant to the bearing, without the aid of any fibrous absorbent whatever.

A represents a bolster, in external form quite like those in common use;

B is an annular chamber for the deposit of a quantity of oil; and

C is the spindle or shaft-bearing.

It will be noticed that the wall of the oil-chamber next to the bearing is not perpendicular to the plane of the bottom of such reservoir, but is inclined thereto, as seen at *a a*. In other words, the metal about the bearing would, if extended so as to meet in a point in the axis of the bearing, make the figure of a cone.

Oil, or other liquid lubricant, having been placed in

the annular chamber B, it will be found that the current of air set in motion by a rapidly-revolving spindle, will cause a film of oil to flow up the inclined side *a a* of the chamber to the bearing, without the employment of any conductor possessing the power of capillary attraction.

The rate of supply of oil to the bearing should be in proportion to the necessities of the case, and can be increased or diminished by varying the angle of inclination of the side *a a* to the axis of the spindle.

The speed of the spindle being known, it will be easy to determine, by experiment, in any particular case, the degree of inclination required for the side of the chamber.

I have found that for spindles making the usual number of turns per minute, the angle shown in the drawings allows the requisite quantity of oil to flow to the bearing. For spindles making less than this number, the angle of the face of the cone-shaped side of the chamber to the axis of the spindle should be proportionately greater, and *vice versa*.

I do not limit myself to any particular angle of inclination to be given to the wall of the oil-chamber, as such angle must be proportioned to the speed at which the spindle is to run.

What I claim as my invention, and desire to secure by Letters Patent, is—

The improvement in bolsters, which consists in constructing the wall of the oil-reservoir B, next to the bearing, with its face *a a* inclined to the axis of the spindle, substantially as described for the purpose specified.

ISAAC P. RICHARDS.
